THE NORRIS PETERS CO., PHOTO-LITHO., WASHINGTON, D. C.

UNITED STATES PATENT OFFICE.

JOHN C. MCKALLIP, OF ATHENS, OHIO.

AUTOMATIC GAS CUT-OFF.

SPECIFICATION forming part of Letters Patent No. 663,661, dated December 11, 1900.

Application filed August 3, 1900. Serial No. 25,805. (No model.)

To all whom it may concern:

Be it known that I, JOHN C. MCKALLIP, a citizen of the United States, residing at Athens, in the county of Athens and State of Ohio, have invented certain new and useful Improvements in Automatic Gas Cut-Offs; and I do hereby declare the following to be a full, clear, and exact description of the invention, such as will enable others skilled in the art to which it appertains to make and use the same.

This invention relates to improvements in automatic gas cut-offs of the character designed to close automatically when the flow of gas is arrested or materially reduced by reason of breakage or leakage in the mains and remain closed until manually opened, so as to prevent the inlet of gas through open burners into the rooms or apartments of a house.

The object of the invention is to provide a simple and effective valve of this character in which the parts are readily accessible and removable for cleaning or repairs and are constructed and arranged in a novel manner to secure the best results.

The invention is illustrated in the accompanying drawings, in which—

Figure 1 is a view in side elevation of my improved automatic gas cut-off. Fig. 2 is a central vertical longitudinal section of the same. Fig. 3 is a cross-section on the line X X of Fig. 2. Fig. 4 is a sectional plan view taken on line Y Y of Fig. 2. Fig. 5 is a perspective view of the valve parts detached. Fig. 6 is a similar view of the device for setting the valve.

1 in the drawings represents the valve-casing, which has an enlarged or swelled central portion 2, which serves as the housing for the valve mechanism, and threaded inlet and discharge passages or ends 3 and 4, which are designed for application to the proximal ends of the house service-pipe adjacent to the meter or at any other desired point where the valve is to be applied. These ends are separated by a partition 5 of ordinary form, which also serves to divide the central portion of the casing into upper and lower chambers or compartments 6 and 7. This partition is apertured in its horizontal portion to receive a screw-threaded cup 8, which cup is

provided in its bottom with a guide-opening 9 and at its upper edge with an outwardly-projecting flange 10, which rests upon the upper surface of said partition, the inner face of the flange, constituting the rim edge of the cup, being beveled, as at 11, to form a seat for a vertically-moving valve 12. This valve controls the passage of gas through the casing and is mounted centrally upon a stem 13, slidable vertically in the guide-opening 9 and a corresponding opening 14 in a guide-plate 15, located above the cup.

The guide-plate 15 is formed integrally with an L-shaped bracket 16, which has its lower horizontal arm secured to an extension 17 of the rim-flange 10 of the cup 8, whereby said cup, the valve, guide-plate, and coöperating parts are adapted to be simultaneously detached for cleaning, repairs, or for other purposes. The upper portion of the valve-stem 13 is thicker than its lower portion and extends upwardly through an opening 18 in a tilting gripping device consisting of a plate 75 or bar 19, mounted centrally upon a fulcrum-post or projection 20 on the guide-plate 15, the said opening 18 being formed in the forward end of said gripping device. This opening is made somewhat larger than the valve-stem, so as to allow the same to move freely therethrough in moving upwardly and to allow opposite portions of the walls thereof to bear frictionally against the stem and prevent the valve from moving downward. The forward end of the gripping plate or bar 19 preferably preponderates in weight, so as to normally cause the bar to assume a downwardly-inclined position. When the valve is moved upward from its seat, the apertured forward end of the gripping device assumes a horizontal position under pressure, and thereby the valve-stem is allowed to have free movement through the opening 14. When the pressure is removed, however, the weight of the front end of the gripping device, as well as the weight of the valve, causes said front end of the gripping device to tilt down and assume an inclined position, whereby the front and rear sides of the wall of the opening 14 are brought to bear 95 frictionally against the valve-stem, and by this means the valve is held open to allow gas to pass through the casing. It will be observed from the foregoing that the valve

mechanism is located mainly in the chamber or compartment 6 and may be removed by simply unscrewing the cup 8.

The upper portion of the valve-casing is open and provided with a cylindrical extension 20^a, which coöperates with a cap 21 and forms therewith a dome or chamber 22. The bottom of this chamber consists of a head or partition 23, clamped between bolting-flanges 10 on the extension and cap or otherwise suitably secured to the casing and having a central opening 24 and an annular depressed portion 25, forming a well or chamber for the reception of a sealing medium, such as mercury. A bell 26 is arranged to move between the said partition 23 and cap 21, and its pendent flange dips down into the said sealing-chamber 25 to prevent the escape of gas in the ordinary manner. To the body or top plate 15 of the bell 26 is threaded or otherwise secured an operating-stem 27, the lower end of which is arranged to slide in the central opening 24 in the partition 23 and contact with the rear end of the gripping-bar 19 to force said bar 20 to a horizontal position, and thereby release the valve when the pressure of the gas falls below a predetermined point and the bell descends. The upper end of the stem 27 projects to the exterior through an opening 28 in 25 the cap 21 and has secured thereto a nut 29 or any other suitable form of projection serving as a finger-piece, whereby the gripping-bar may be manually operated, and as a stop to hold the stem and bell in place when the cap 30 is removed.

In the operation of the device the valve 12 is normally held open in elevated position by the gripping-bar 19, which is tilted, with its front end depressed and its rear end elevated 40 and located immediately beneath the stem 27. When the valve is thus held open, the pressure of the gas passing through the casing will force the bell 26 upward and hold the lower end of the stem 27 above the said rear 45 end of the bar 19; but when the flow of the gas through the casing is arrested by reason of breakage or leakage in the mains, the bell, being no longer supported, will drop down, thereby causing the lower end of the stem 27 50 to contact with the rear end of the bar 19 and force said bar to a horizontal position. The opening 18 in the bar will thus be restored to a vertical position, and the stem 13 being no longer frictionally gripped, the valve 12 will 55 drop down upon its seat 11 and close the port, so as to prevent any passage of gas into the service-pipe. By this means the flow of gas into the service-pipe will be arrested until the valve is again lifted off its seat and held open 60 by the friction-bar, so that the inlet of gas through open burners into the rooms or apartments of the house when the flow of gas from the main into the service-pipe is resumed will be prevented and all liability of explosions 65 and danger of asphyxiating the occupants of the house entirely obviated, as the resump-

tion of the flow of the gas will have no effect upon the opening of the valve.

The valve is adapted to be opened from the exterior through the medium of a shaft or 70 spindle 30, journaled in the side wall of the casing and carrying at its outer end a hand-wheel or other suitable operating device 31. The inner end of this shaft or spindle projects into the chamber or compartment 7 and 75 carries an arm 32, that is adapted to be elevated by turning the shaft to cause it to contact with the lower end of the stem 13 and force said stem and the valve upward. A coiled spring 33, secured at its opposite ends 80 to the arm 32 and wall of the casing, serves to retract the shaft and arm and hold the same in their normal position, so as to prevent casual movement and operation of the valve, as will be readily understood. By 85 means of the construction and arrangement of parts shown and described the valve may be opened and closed at any time desired independent of the gas-pressure, as the friction-bar may be forced down to release the valve 90 when it is desired to shut off the flow of gas and the valve opened when it is desired to let on the flow of gas through the medium of the hand-wheel and its connections.

A flexible diaphragm of ordinary construction may be substituted for the bell herein shown and other changes in the form, construction, and arrangements of the parts made within the scope of the invention without departing from the spirit or sacrificing any of the 95 advantages thereof.

Having thus described the invention, what is claimed as new is—

1. In an automatic fluid cut-off, a casing, a valve-seat located wholly within the casing 105 and removable through a cap-covered opening in the side thereof, a valve-support attached to and movable with the valve-seat, a stemmed valve guided in its movements by having its stem acting jointly with the valve-seat and valve-support, and a gripper fulcrumed to the valve-support and adapted to hold the valve open at any point, substantially as described.

2. In an automatic fluid cut-off, a partitioned casing having a cap-covered side opening, a valve-seat removable through the said cap-covered opening, a bracket attached to the valve-seat, a stemmed valve directed in its movements by having its stem working in 110 openings formed in portions of the valve-seat and bracket, a gripper fulcrumed upon said bracket and adapted to hold the valve open at any distance, a manually-operated device 115 for unseating the valve, and a fluid-pressure-controlled device adapted to release the valve, substantially as described.

3. In a valve of the character described, the combination of a casing having a partition provided with an opening, a cup fitted 120 in said opening and forming a valve-seat and provided in its bottom with an aperture, a

bracket attached to the cup and having an overhanging portion provided with a corresponding aperture, a valve movable between the cup and overhanging portion of the bracket and having upper and lower stem portions slideable in said apertures, a gripping device fulcrumed to the bracket and adapted to engage the upper stem portion to hold the valve open, and a fluid-pressure-controlled

device adapted to engage the gripping device 10 and effect the release of the catch, substantially as described.

In testimony whereof I affix my signature in presence of two witnesses.

JOHN C. MCKALLIP. [L. S.]
